BARBECUE SPIT BASKET

Herbert A. Elliott, 604 Middle St., Webster City, Iowa

Filed Mar. 30, 1964, Ser. No. 79,247

Term of patent 14 years

(Cl. D81—10)

Fig. 1

I claim:

The ornamental design for a barbecue spit basket, substantially as shown and described.
